UNITED STATES PATENT OFFICE.

JOSHUA P. MADDOX, OF PORTLAND, MAINE.

FABRIC FOR MACHINE-BELTING, &c.

SPECIFICATION forming part of Letters Patent No. 400,579, dated April 2, 1889.

Application filed March 1, 1889. Serial No. 301,594. (No specimens.)

To all whom it may concern:

Be it known that I, JOSHUA P. MADDOX, a citizen of the United States, residing at Portland, in the county of Cumberland and State 5 of Maine, have invented certain new and useful Improvements in Fabrics for Machine-Belting and for other Purposes; and I do hereby declare the following to be a full, clear, and exact description of the invention, such as will 10 enable others skilled in the art to which it appertains to make and use the same.

My invention relates to that class of fabrics used for machine-belting wherein metal wire is used for a warp or is laid in the fabric longitudinally for the purpose of bearing the strain. These fabrics have heretofore been woven in a single ply formed of wire warp and a fibrous weft, and they have also been woven of two or more plies. Where the fabric has been woven of two or more plies, the wire has either been "laid in" between the plies, in which case it did not form a proper warp, the various plies having been held together and held in contact with the wire by 20 running binders from one face of the fabric completely through to the other, or the wires have been interwoven with a weft-thread forming a separate ply, the exterior plies of fibrous material being bound together and 25 upon the middle partly-metal ply by binders passing completely through the fabric from one face to the other. One difficulty with belting of this character has been that the wire when not bound firmly to the facing- 30 plies has had a tendency to creep or move longitudinally in the body of the belt. This defect has been particularly apparent near the ends of the belt where by the ordinary modes of fastening—such as lacing, &c.—the 35 40 fastening passed between the wires and depended for its holding power on the firmness with which the wire was bound to the fibrous threads. It is thus desirable to have these parts as firmly knit together as possible.

The object of my invention, therefore, is to devise a fabric in which the warp-wires shall be bound as completely as possible to the fibrous threads, thus preventing any movement of the warp-wires in the body of the 45 50 fabric, and also enabling a strong laced or other joint to be made, as in ordinary leather belts.

My invention consists of a fabric having an inner ply composed of wire warp and fibrous weft and facing-plies on either side thereof, 55 and bound thereto by binders extending from said facing-plies to said inner ply and back, and interlocking with the weft of said inner ply. Such a fabric I have illustrated in the accompanying drawings, in which I represent a five-ply fabric constructed according to my invention.

In the drawings, Figure 1 is a longitudinal section of my improved fabric, and Fig. 2 is a transverse section on the line *x x* in Fig. 1. 65 Fig. 3 is a general plan view with parts cut away.

A represents a weft thread or threads, B the fibrous warps, and D the wires. As shown, the weft A is interwoven with the wires D in 70 a manner to form therewith a single ply, the said weft being shown in Fig. 2 as first carried from the right-hand side of the fabric to the left, interweaving with the wires D, and then back again from left to right, interweaving 75 with the wires D. The weft A is next interwoven with the fibrous warps B of the inner ply below the wires and then with the fibrous warp of the inner ply above the wires. Finally, the weft passes from right to left, 80 interweaving with the fibrous warp of the outer ply below the wires D, and then returns from left to right again, interweaving with the fibrous warps of the outer ply above the said wires. The manner of weaving described 85 produces five superimposed plies of fabric. In order to bind the whole together and hold the wires and fabric securely in such a manner as to prevent them from having any longitudinal movement whatever, I employ binding-warps E. These warps pass from the middle of the fabric outward to the opposite faces of the fabric, extending around the weft-threads of the outmost plies, and then returning to the innermost ply—namely, that 90 composed of the interwoven fibrous weft and warp wires—and then again pass around the weft-threads of said innermost ply.

Instead of using one weft passing in turn through each one of the various plies of the 100 fabric, two or more separate wefts variously interweaving with the various plies may be employed.

Instead of two plies composed of fibrous

warps and wefts on each side of the wires, I may form one ply only, or I may form more than two, if desirable. The wire D, I prefer to use of sufficient size so that it will lie in the fabric nearly straight or with slight deflection, the weft-threads C of the inner ply being thus caused to cross each other. The binders E E are in two sets, extending in from the outer ply of each face and interlocking 10 with the weft-threads of the inner ply. The binders from each face interlock with alternate weft-threads of the inner ply, as here shown. As a result of this construction the alternate weft-threads of the inner ply are pulled by the binder-warps in opposite directions, so that the wire is securely held and prevented from having any longitudinal motion. By this means I am enabled to use 15 wires of larger size than are practicable in other belts, for the reason that the binding to the wire is more firm.

As here shown I have made every alternate warp-thread on either side a binder; but I may use a greater or less number of wires and binders, according to the strength required and the size of the wire.

The fabric here shown will be found well

adapted for use where great longitudinal strength is required. The wires will be closely knit to the body of the fabric and will not move longitudinally in the belt. They may be of comparatively large size, and yet be kept firmly in place by the binding effect of the binding-warp. A pull on the binders exerts a binding tension on the wire at every pick, 35 and so retains it solidly in place.

I claim—

The herein-described fabric for machine-beltting and for other like purposes, having an inner ply composed of a wirewarp and a fibrous weft, and one or more plies of facing material of fibrous material on each side of said inner 40 ply and bound thereto by binders extending from said facing-plies to the said inner ply and back through said facing-plies and interlocking with the weft of said inner ply, substantially as shown.

In testimony whereof I affix my signature in presence of two witnesses.

JOSHUA P. MADDOX.
